(57) **CLAIM**

The ornamental design for a metal detector, as shown and described.

DESCRIPTION

FIG. 1 is a front perspective view of a metal detector showing our new design in a collapsed configuration;
FIG. 2 is a top view thereof in a collapsed configuration;
FIG. 3 is a front elevation view thereof in a collapsed configuration;
FIG. 4 is a right side elevation view thereof in a collapsed configuration;
FIG. 5 is a bottom view thereof in a collapsed configuration;
FIG. 6 is a rear elevation view thereof in a collapsed configuration;
FIG. 7 is a left side elevation view thereof in a collapsed configuration;
FIG. 8 is a front perspective view thereof in an expanded configuration;
FIG. 9 is a front elevation view thereof in an expanded configuration;
FIG. 10 is a right side elevation view thereof in an expanded configuration;
FIG. 11 is a rear elevation view thereof in an expanded configuration;
FIG. 12 is a left side elevation view thereof in an expanded configuration;
FIG. 13 is a top view thereof in an expanded configuration;
and,
FIG. 14 is a bottom view thereof in an expanded configuration.
